UNITED STATES PATENT OFFICE.

JOHN EDWARD RABY, OF NEGAUNEE, MICHIGAN.

METALLIC RAILROAD-TIE.

No. 909,220.

Specification of Letters Patent.

Patented Jan. 12, 1909.

Application filed July 7, 1908. Serial No. 442,869.

To all whom it may concern:

Be it known that I, JOHN EDWARD RABY, citizen of the United States, residing at Negaunee, in the county of Marquette and State of Michigan, have invented certain new and useful Improvements in Metallic Railroad-Ties, of which the following is a specification.

This invention relates to metallic railroad ties intended as a substitute for the ordinary wooden ties used on railways, and has for its object to provide an improved tie made from a plate of metal such as steel bent or pressed to shape, in such manner as to form a stout and rigid tie having various advantages, as will more fully appear from the following description and the accompanying drawings.

In the drawings, Figure 1 is a plan view 20 of the tie. Fig. 2 is a partial longitudinal section. Fig. 3 is a cross section on the line 3—3 of Fig. 2. Fig. 4 is a perspective of a device for bracing and fastening the rail base. Fig. 5 is a detail in perspective showing the bolt which fastens the rail in place and which holds the brace shown in Fig. 4 in position.

The tie is of the box type, at the ends, at least, and is made of pressed steel or the like bent to form opposite vertical sides 6 connected at the ends by a bottom 7, with an opening 8 in the bottom at the middle, to allow the escape of water or the like. The ends of the sides are inclined, as indicated 35 at 9, and the ends of the bottom are turned up against the ends of the sides, as shown at 10.

A top part or piece 11 extends across between the sides, at the ends of the tie, and 40 said top plate has a longitudinal depression indicated at 12 forming a seat for a wooden block 13. This depression is of less width than the width of the top plate, and is located at the middle line of the tie, forming 45 on each side internal channels or recesses 14 which serve a purpose to be hereinafter explained. The block 13 is preferably somewhat thicker than the seat, so that the rail 15 does not rest upon the metal part of 50 the tie, but is supported on the block. Said block is partly covered by a thin plate 16 on which the rail rests, said plate being bent up and over at its inner end, as indicated at 17, to form a clip which engages over the 55 base of the rail. At the outer end the plate

is bent down, as at 18, over the end of the wooden block, and the side edges of the plate are also bent down, as at 19, so that the block is substantially covered and protected. 60

The tie is strengthened by internal arched braces 20 located under the rail seats, and consisting of metallic pieces bent to fit within the tie and bolted to the top plates, as indicated at 21. This prevents crushing 65 of the tie, incident to the weight on the rails, and enables the tie to be made of lighter metal than would otherwise be possible. The wooden blocks on which the rails are seated, give a certain amount of spring or 70 yield to the tie, and distribute the weight over a larger space than if the rails rested directly on the metal part of the tie.

To fasten the rails to the tie I use angular pieces 21, as shown fully in Fig. 4, and bolts 75 22 having flanged heads. The lower ends of the angular pieces 21 are adapted to fit in holes punched for that purpose in the top 11 of the tie, on opposite sides of the rail base, and the upper angle or part of the piece 21 80 rests upon the top of the tie with its end against the edge of the base of the rail, said end having a recess 23 therein through which the bolt 22 extends. Said bolt extends through a hole in the top of the tie and 85 engages a nut 24 which fits closely in the channel 14, above referred to. This prevents the nut from turning, and enables the bolt to be screwed down tight by a wrench applied to the head thereto, and said head 90 then laps the edge of the rail base as well as the end of the piece 21. The angular pieces 21 thus prevent any side slip or lateral displacement of the rails, but the rails may be quickly removed by taking out the bolts 22. 95 The lateral pressure on the rail is supported mainly by the angular pieces 21 which communicate the strain directly to the tie, the bolts simply acting to hold said angular pieces in place and to prevent jumping of 100 the rail. In order to accommodate rails of different weights or sizes, several sets of holes may be made in the top plate 11 for the angular pieces and the bolts.

It will be seen that the tie is made of few 105 parts which are simple in construction and easily put together, while at the same time strong and durable. The use of the wooden block gives great elasticity to the track, which is an uncommon advantage for steel 110

ties, and the fastening devices make lateral displacement practically impossible. The manner in which the nuts 24 are held in the channels under the top of the tie is efficient and advantageous, inasmuch as the nut and thread are protected and cannot be battered in any way. The tie plates 16 protect the wooden blocks from weather and wear and also hold the same in place under the rail. 10 The tie plates may, however, be omitted if desired, and other devices used for holding the wooden blocks. The blocks are useful and desirable because they can be varied as desired, to raise or lower the rails. High or 15 low spots in the track can be corrected by substituting thicker or thinner blocks, or the blocks for a short space can be taken out entirely, letting the rail rest on the tie directly. The tie can be rolled, cast or pressed from a 20 single sheet of metal and the edges made to meet where desired, preferably at the middle of the top.

Various modifications may be made within the scope of the following claims, and no

limitation is implied by reason of the particular construction shown. 25

I claim:

1. A hollow metallic tie having depressed seats in the top thereof, of less width than the width of said top, forming channels on 30 the under side of said top, and bolts to fasten the rails, extending through the top and having nuts thereon held from rotation in said channels.

2. A hollow metallic tie provided with 35 wooden blocks upon the ends thereof, and plates upon the blocks, on which plates the rails rest, the inner ends of the plates being folded over to engage the rail base and the outer ends of the plates being bent down 40 against the ends of the blocks.

In testimony whereof I affix my signature, in presence of two witnesses.

JOHN EDWARD RABY.
